UNITED STATES PATENT OFFICE.

CHARLES G. BROSTROM, OF LYNN, AND ANDREW R. RIDDERSTROM, OF NAHANT, MASSACHUSETTS, ASSIGNEES TO BEACON FOLDING MACHINE COMPANY, OF LYNN, MASSACHUSETTS, A CORPORATION OF MASSACHUSETTS.

FOLDING MACHINE.

Original application filed May 12, 1917, Serial No. 168,165. Divided and this application filed May 3, 1924. Serial No. 711,004.

To all whom it may concern:

Be it known that we, CHARLES G. BROSTROM and ANDREW R. RIDDERSTROM, citizens of the United States, and residents, respectively, of Lynn and Nahant, in the county of Essex and Commonwealth of Massachusetts, have invented a new and useful Improvement in Folding Machines, of which the following is a specification.

10 The present invention relates to machines for folding flexible material. The present application is a division of a copending application, Serial No. 168,165, filed May 12, 1917.

15 The present invention is hereinafter described, and is illustrated in the accompanying drawings, in connection with a machine for folding or turning over the margins or edges of boot or shoe uppers, such as 20 vamps, tips and the like. The invention is not, however, restricted to machines of this character, but has also other and more general fields of usefulness. Machines for 25 folding binding strips around the edges of shoe uppers to which they are sewed, machines for turning the channel flaps of channeled shoe soles, and other machines for folding flexible material are all included within the present invention. In order 30 to avoid circumlocution of language, all such machines will hereinafter be included in the specification and, more particularly, in the claims, under the generic term "folding machines"; and it will be understood that the term "margin" or the term 35 "edge" will be employed herein to denote not only the border portions of a shoe upper, but also a marginal binding strip, the channel flap of a channeled sole, and 40 other such parts that are intended to be folded in the defined "folding machine."

According to present-day practice in shoe manufacture, after the margin of a boot or shoe upper has been cemented, the upper is 45 introduced into the machine, in which it is advanced, step by step, past a knife and a folder or plow, to a fold presser, or hammer. The knife is controlled to snip the margin, when desired, the plow acts to 50 initiate the fold, and the fold thus initiated is pressed down by the fold presser, being held in pressed condition by the ce-

ment. In those commercial folding machines the feed mechanisms of which comprise vibratory feed points and feed blocks, 55 the feed elements are operated by spring-controlled cams. Owing to inherent time lags, the feed elements can not respond readily enough to the action of the operating instrumentalities, and so can not be 60 employed in high-speed machines. A feature of the present invention, accordingly, contemplates a positive connection between the feed elements and their operating instrumentalities, thus eliminating 65 the above-referred-to time lags.

If the stock is advanced by relatively short feed strokes, sharp curves will be folded more readily. The comparative slowness of operation resulting from the 70 use of short feed strokes may be compensated for by operating the machine at higher speed. In fact, if the speed of operation is high enough, the folding operation as a whole may be increased to a 75 value above that commonly prevailing. Curved portions of the work, however, should be advanced less rapidly than straight portions, so that a small portion only of the margin may be folded at any 80 one time, and a better approximation thereby attained to a smooth, curved fold. A further object of the invention, therefore, is to provide improved means controlled manually, preferably by a progressively 85 movable treadle, for gradually moving the feed elements relatively towards and from each other, to increase and decrease gradually the length of the feed strokes. To the attainment of this end, a feature of the invention resides in swinging one of the feed members, as the upper feed point, from its operating point as a fulcrum, so as to render it effective to a varying extent during different feed strokes. According to the 90 specific embodiment of the invention that is herein illustrated and described, the feed point is carried by a leaf spring that is secured to its operating device at a point relatively remote from the feed point.

A still further object is to provide an improved, manually controlled construction, comprising a single treadle, for controlling the power clutch and also for elevating

and depressing the upper feed point, to render the same varyingly effective or ineffective, at will. By actuating the treadle, therefore; first, the clutch may be thrown in, to start the machine; and then, by a further movement of the treadle, the feed point may be depressed and the effective feed movement started.

The foregoing and other objects and advantages of the invention will more fully appear from the following detailed description, and the distinctive features of novelty will be pointed out in the appended claims.

Referring to the drawings, Fig. 1 is a central, longitudinal, vertical section of a machine constructed in accordance with the present invention; Fig. 2 is a fragmentary detail, illustrating the immediate working parts in side elevation; Fig. 3 is a detail front view of the machine; Fig. 4 is a partial view of the front of the machine, with certain parts removed, and others in section upon the line 4—4 of Fig. 1, looking in the direction of the arrows, to illustrate the immediate working elements; Fig. 5 is a sectional detail on line 5—5 of Fig. 1, looking in the direction of the arrows; Fig. 6 is a fragmentary perspective, showing a vamp and the immediate working parts in operative relation thereto; Fig. 7 is a fragmentary detail, in section upon the line 7—7 of Fig. 2, looking in the direction of the arrows, also showing the immediate working parts in operative relation to a vamp; Fig. 8 is a vertical section taken upon the line 8—8 of Fig. 1, looking in the direction of the arrows, showing the working parts in detail, acting on a vamp; and Fig. 9 is a detail similar to Fig. 8, showing the operative parts occupying another position.

The frame or housing of the machine comprises a body portion 10, extending up into a curved overhanging portion 11, with a forwardly extending nose 12. The nose 12 is spaced from the body of the frame above an extension 13, the extension 13 constituting what is known as the "horn" of the machine. The frame is equipped with a bearing 14 to receive the rear portion of a drive shaft 15, in substantially the plane of the feed elements, referred to below. The forward end of this shaft is journaled in a separate bearing bracket or sleeve 16, which may be rigidly secured to the frame by a cross pin or rod 17. For adjustably centering the bearing sleeve 16, transverse screws 115 are fitted from opposite sides, through web portions of the machine housing, to engage the sleeve at opposite points.

A hand-and-balance wheel 18 is keyed or otherwise suitably secured upon the outer end of the shaft 15, and is provided with a clutch face 19. The clutch face 19 is adapted to be frictionally engaged by a co-operative clutch face on the inner side of a driv-

ing pulley 20 that is fitted on a sleeve 21. The clutch face of the pulley 20 is normally held away from the clutch face 19 by a coil spring 22 that is housed in a recess between the wheel 18 and the pulley 20. The sleeve 21, which is slidably fitted loosely on the shaft 15, has a head 9. The pulley 20 is maintained in engagement with the head 9 by the spring 22. A head 23 is fitted in the outer end of the sleeve 21 and is engageable by a wear button 24, that is constituted of fibre or the like, and that is carried at the upper, outer end of a lever arm 25. The lever arm 25 is pivoted to the frame at 26 and is rigidly provided with a long, horizontally extending arm 27. The arm 27 reaches most of the way toward the front of the housing, where its extremity is slotted to receive therein, with a capability of end-wise sliding, a pivot block 28. The pivot block 28 is carried at one end of a short, lever, link bar 29, the other end of which is pivoted at 30 to the end of one arm 31 of a bell-crank lever. The bell-crank lever is fulcrumed at 45 and its other arm 32 has an adjustable stop pin 33 fitted in its extremity adapted to engage the frame as an abutment to limit the swinging movement of the said lever in one direction. The swinging of the said lever in the other direction is yieldably limited by an adjustable, headed bolt 34 threaded into the frame and having a coil spring 35 interposed between its head and a seat in the lever arm 32. The lever bar 29 is pivotally connected at an intermediate point 36 to a depending bracket 37, the pivot connection 36 being, as shown, nearer to the pivot block 28 than to the pivot 30, for reason that will later appear. The bracket 37 has a shoulder 38 formed thereon underneath the pivot 36 and is equipped with a depending pin 39 slidably fitted through a bearing strut 40 of the frame. A compression coil spring 41 is interposed between this strut and the shoulder 38. Upon release of the treadle, the coil spring 41 will return the lever arms 27 and 31 to their illustrated, ineffective positions, permitting the spring 22 to disconnect the clutch faces and also elevating the feed point, as will later appear. The bracket 37 is provided with an offset portion having a pivot connection 42 to a depending rod 43. The rod 43 is adapted to be connected to a treadle (not shown), and typifies any suitable control, preferably manual, for the power clutch and also for the upper feed point.

For applying a brake to the machine by the same operating device that controls the power clutch, a short, brake lever arm 104 is mounted on the pivot 26. The arm 104 is provided with a brake shoe 105 that is adapted to engage the periphery of the wheel 18. The arm 104 has a downward

extension 106 below its pivot 26, where it is engaged by a screw 107 that is adjustably carried in a lug 108, rigid with and depending from the arm 25. Thus, upon an upward movement of the arm 27, to disengage the driving-clutch elements, the pin 107, by engaging the extension 106, applies the brake at a time predetermined by the adjustment of the screw 107.

10 The lower end of a vertically disposed link bar 46 is pivoted to the lever arm 31 at 44, relatively close to the fulcrum 45. The upper end of the link bar 46 is pivoted at 47 to the inner end of a frame plate 48. 15 The frame plate 48 is pivoted to swing in a vertical plane about a pivot pin 49 that is transversely fixed in the frame of the machine, and is provided with a vertically disposed pivot post 50. The base of a 20 bracket mounting 51 is pivoted to swing or rock horizontally about the post 50 as an axis, on a bearing surface provided at the top of the plate 48. A lower feed block 53 is clamped, as shown at 52, to the forward 25 end of the bracket mounting 51, and is provided with a plow 116 for turning up the margin of the stock, as will be more fully explained later. The bracket mounting 51 has spaced-apart, rearward, wing extensions or ears 54, bearing a transverse pivot pin 55 that constitutes a pivot or axis for a lever arm 56. The lever arm 56 is thus adapted to swing vertically on an intermediate disposed pivot pin 55 that is 30 transversely secured between the extensions or ears 54, and also, with the mounting 51 to swing or rock horizontally about the vertical pivot pin 50. A leaf spring, in the form of a resilient plate 58, is clamped 35 to the lever arm 56, at its inner end, and relatively remote from the pivot 55, as seen at 57. The leaf spring 58 extends forward well beyond the pivot 55, to constitute a 40 resilient yielding mounting for the upper feed member 59 which, as shown, is integral with the said spring plate. This upper feed member comprises a downwardly and inwardly turned extremity, terminating in a 45 downwardly projecting feed point 60, opposite the lower feed block 53. By means of this construction, the use of separate, spring-controlled cams is rendered unnecessary, so that the feed elements may be positively connected to their operating instrumentalities. The inner end of the lever arm 56 is formed with a socket 61, in which is fitted a ball head, mounted on a crank pin 62, which is carried at the end of the 50 drive shaft 15.

55 As the shaft 15 is rotated, the lower feed block 53 is oscillated by the crank pin 62 in a horizontal plane about the axis 50. The upper feed member 59 also partakes of this horizontal oscillation and is at the 55 same time endowed with a vertical oscillation about the horizontal axis 55. It is in consequence of the horizontal oscillations that the feed members are caused to produce the feed movement, and the vertical oscillation causes the feed point to grip and release the work alternately. The path that the feed point 60 follows is curved, generally oval in nature. The feed point presses the material against the lower feed block 53 whenever the treadle rod 43 is depressed. Depression of the treadle rod effects a downward movement of the link bar 46 and a corresponding swinging movement of the plate 48 about the pivot pin 49. This movement of the plate 48 results in a relative movement towards each other of the feed block and the feed point, both of which it supports. The more that the treadle rod is depressed, the closer will the feed point and the feed block be caused to approach each other; with the result, as the feed point is carried by the spring plate 58, and yields upward by spring action, that the oval path of the feed point will become more and more flattened. The flatter the oval path of the feed point, the sooner will the material be engaged between the feed point and the feed block on each feeding movement, and the longer will each such engagement take place. The arm 56, carrying the feed point, of course, moves through the same range with the feed block, during every intermittent feed movement; but the feed point is caused to engage the material earlier and earlier, before the completion of its downward movement, the farther and farther that the treadle rod is depressed. According to the degree of depression of the treadle, therefore, the feed point may be caused to engage the material to feed it through longer or shorter feed strokes, as desired.

60 The mounting 51 is equipped with an adjustable stop screw 63, adapted to determine the final limit of downward movement of the feed point 60, and the frame is equipped with spaced stops 64, 65 for co-operation with the bell-crank lever arms 31 and 32. The stops 64 and 65 limit the described operative movement of the treadle in opposite 65 directions, thereby determining the final limits of feeding movement of the upper and lower feeding elements.

65 For completing the folding over of the margin of the vamy, after it is turned up by the plow on the lower feed block, as more fully explained later, and for hammering or pressing down the same, a hammer 92 is provided which, as shown more particularly in Fig. 3, is pivoted to the same pivot pin 49 that serves as a pivot for the mounting 48. The hammer 92 is held from movement in the line of feed and is normally inclined, extending obliquely upward and outward. Its lower end is pivotally 70

connected to a collar 93 that is slidably carried on an operating rod 94. The collar 93 is held for limited movement between a stop collar 95 on the rod 94 and a stop head 96 carried at the end of the said rod, and is normally held yieldingly against the collar 95 by a coil spring 97 that is interposed between the collar 93 and the head 96. The inner end of the rod 94 is pivotally connected at 98 to the lower end of a short lever 99. The lever 99 is fulcrumed to the frame at 100 and its upper end is provided with a contact piece 101 that is engageable with a cam face 102 fixed on the shaft 15. A coil spring 103 is anchored to the pivot 100 and engages the upper portion of the lever 99, thus pressing the said upper end of the said lever constantly against the cam 102. The hammer 92 is therefore oscillated in timed relation to the feed movements. The hammer blows are rendered yielding or resilient to the required extent by reason of the interposed spring 97, while the upward movement of the hammer is rendered positive by engagement of the fixed collar 95 with the slide collar 93.

A table is indicated at 109, and is shown fitted around the platform 110 at the front 30 of the horn, this platform being a relatively small plate block adjustably clamped to the top of the horn, and the table 109 being recessed, as seen at 111, to fit down over the same. The table has projections 112 at each side of the machine housing, extending to a point well rearward thereof, where their extremities are fulcrumed, as seen at 113, to transverse pivots carried by the housing. The forward portion of the 40 table is adjustably supported by prop posts 114 that are vertically threaded into the frame housing at each side thereof, the adjustment of these prop posts permitting the table to be adjustably set so that its top surface will be approximately flush with the 45 surface of the platform 110.

Referring now more particularly to the immediate working parts, as hitherto explained, the stock is gripped for feeding 50 between the lower feed block 53 and the upper feed point 60. On the lower feed block 53 is carried the "plow" or folder 116, presenting a curving face of changing outline, as shown more particularly in Fig. 55 6, adapted to catch the horizontally extending edge of the vamp V and turn the same up to an approximately vertical position. The feed point and the feed block 53 are adapted to engage the material at a 60 point such that the line joining this point to the plow 116 is substantially at right angles to the line of feed. The plow and the feed elements are therefore as effective, both to fold and to feed, at sharply curved 65 portions of the margin, as at straight por-

tions. If the plow were at a substantial distance forward of the feed elements, for example, a sharply convex portion of the stock would be moved by the feed elements out of range of the plow, so as not to be 70 folded at all thereby, and a sharply concave portion would be folded too far over by the plow. The hammer 92 is formed with a horizontal extremity for engaging that portion of the work that is located 75 just beyond the feed members, along the line of feed. The operating mechanism is timed so that the hammer shall move down to grip the turned-over edge of the stock, as seen in Fig. 9, during the time that the 80 feed members are moving backward, preliminary to getting a new grip on the stock. In the said Fig. 9, the feed members are illustrated in the positions that they occupy just prior to their return movement. During 85 this return movement, the plow 116, which moves with the feed block 53, performs the described operation of turning up the edge of the vamp. The upper feed point 60 is, as shown, provided with a forwardly projecting finger 117 that is adapted to extend over and engage and guide the margin of the stock, just in advance of the plow, so as to hold it against the plow and 90 keep it from buckling up prematurely, prior to the action thereon of the plow. A snapping knife 63 is arranged for cooperation with a fixed knife block 67 mounted on the horn portion of the frame, just in advance of the plow 116, along the line of 95 feed, as shown in Figs. 6, 7 and 8, and the operating device of this knife is preferably timed to cause it to operate once at every other feed movement. Since the hammer 92 is mounted to extend obliquely 100 upward and forward, its action on the edge of the stock will be in the same oblique direction, thus insuring the proper turning down of the margin of the vamp, that has 105 already been turned upward by the plow 116. 110

In use, the operator, introducing the vamp V into the machine, places the margin thereof on the lower feed block 53. At this time, when the machine is idle, the feed block is relatively depressed under the action of 115 the spring 41, and the upper feed point 60 is correspondingly lifted, so that ample room is afforded for inserting the work. Upon depression of the treadle rod 43, the lever link 29, first swinging on the point 120 30 as a fulcrum, since the pivot 36 is nearer to the point 28, operates the lever 25, to throw in the clutch elements 19, 20, starting the machine. The feed members thereupon begin their cycle of movements, but 125 still separated and ineffective. When the operator wishes to begin work, he now further depresses the treadle rod 43. This causes the link 29 to swing on the point 28 130 as a fulcrum, since this point can move

no further, and the link 29 swings downward the lever, thus effecting a turning movement of the mounting 48 about the pivot 49 to elevate the feed block 53 into its effective plane. At the same time, the pivot 55 of the arm 56 is moved downward, causing this arm to swing downward about the bearing 61 as a fulcrum. The feed member 59 is thus actuated, with a multiplied movement, into effective position. If the operator desires a relatively slow feed, he depresses the treadle rod 43 to a relatively lesser extent, which causes the feed point 60 of the feed member 59 to engage the material through a small portion only of its lower range of movement. The feed point is in this manner caused to describe a relatively wide or broad oval path, so that the material is only moved forward a little at each step. If, however, a more rapid feed is desired, the treadle rod is depressed further, causing the arm 56 to become tilted further, and this will result in the spring-plate mounting 58 of the upper feed point becoming placed under spring tension. The feed point 60 will therefore engage the material sooner, and remain in engagement with it longer to effect a longer range of feed. At this time, the spring plate 58 yields resiliently to permit the arm 56 to continue operating in an oval path, though the feed point 60 is constrained to move, during this feed movement, in a straight path,—with the result that the feed point describes approximately a more or less flattened oval. The feed may thus be varied, at will by depressing the treadle rod 43 to a greater or less extent, as desired by the operator.

40 The invention may be embodied in other specific forms as to its various details, and certain of the features of novelty described may be advantageously used apart from others of the present combination, and it is therefore desired that the present embodiment be considered in all respects as illustrative, and not restrictive, reference being had to the appended claims, rather than to the foregoing description, to indicate the scope of the invention.

50 What is claimed is:

1. A machine of the class described having, in combination, two feed elements one mounted upon the other, and means for simultaneously moving each element towards the other.
2. A machine of the class described having, in combination, a feed block, a feed point normally separated from the feed block, and treadle-actuated means for actuating the feed block towards the feed point during the operation of the machine.

60 3. A machine of the class described having, in combination, a movable support, a feed point and a feed block supported by

the support, and means whereby movement of the support effects a relative movement of the feed point and the feed block.

4. A machine of the class described having, in combination, a movable support, step-by-step feed means comprising a feed block rigidly secured to the support, and a feed point pivoted to the support, and means whereby, upon movement of the support, the feed point becomes separated from the feed block.

70 5. A machine of the class described having, in combination, a feed point and a feed block mounted and connected so that the feed point describes an orbital movement, and means for moving the feed block towards the feed point, whereby the feed point is caused to engage the material for a variable interval on each feed stroke.

80 6. A machine of the class described having, in combination, a support, a feed block, carried by the support, a feed point pivoted to the support, and an eccentric positively connected to one of the said feed elements for vibrating the feed block and the feed point and actuating the feed point relatively to the feed block.

85 7. A machine of the class described having, in combination, two feed elements, one mounted upon the other, one of the feed elements being pivotally mounted upon a floating pivot, and means for actuating the feed elements about the floating pivot to effect a simultaneous movement of each feed element towards the other feed element.

90 95 8. A machine of the class described comprising feeding means for advancing sheet material composed of elements relatively and progressively adjustable towards and from each other to variably effective and ineffective position, means for holding said feed elements normally separated in ineffective position, and treadle-operated means having equipment for causing said elements to be moved relatively towards each other to effective position variably so as to feed more or less rapidly, at will.

100 9. A machine of the class described comprising material-feeding mechanism composed of a lower feed block and an upper feed point having a range of relative adjustment towards and from each other from ineffective to effective positions, spring means for holding said elements normally ineffective by maintaining them separated, and a treadle rod connected for moving said elements relatively towards each other to render said elements effective on actuation thereof.

115 10. A machine of the class described having, in combination, normally ineffective means adapted to vibrate between definite limits to feed material, and means for rendering the feed means variably effective so as to feed more or less rapidly, at will,

- without varying the extent of the feed strokes.
11. A machine of the class described having, in combination, two feed elements adapted for reciprocation to feed material, one of said elements being movable about an axis at an angle to the path of reciprocation, and means for shifting the axis to move said element into and out of effective position relative to the other element.
12. A machine of the class described comprising feeding mechanism comprising a lower feed block and an upper feed point, the feed block and the feed point being mounted and connected for swinging vibration for yielding movement with respect to each other, whereby said feed point describes an orbital movement with respect to said feed block and means for shifting the range of such orbital movement with respect to said feed block, whereby said feed point is caused to engage the material for a variable interval on each feed stroke, at will.
13. A machine of the class described having, in combination, means comprising a spring feed point for feeding material by relatively short feed steps, a feed block co-operating with the feed point, means for operating the feeding means at relatively high speed, and a positive connection between the feeding means and the operating means.
14. A machine of the class described having, in combination, normally ineffective feeding means, driving means therefor, and movable means having two positions in one of which it renders the driving means effective to actuate the feeding means and in the other of which it renders the feeding means effective to feed material.
15. A machine of the class described hav-
- ing, in combination, feeding mechanism comprising an element movable into and out of operative position during the operation of the machine, driving means therefor, and common means for controlling the driving means and the position of the element.
16. A machine of the class described having, in combination, feeding mechanism having an element movable into and out of effective position during the operation of the machine, driving means therefor having a disconnecting clutch, and a single manual control for said clutch and for said feeding means connected to first shift said clutch into engagement and by a further movement to bring said feeding mechanism into effective position.
17. A machine of the class described having, in combination, a continuously operable feed element alternately occupying an effective position during its feeding movement to feed material and an ineffective position during its return movement, means for driving the feed element, and common means for controlling the driving means and the effective position of the element.
18. A machine of the class described having, in combination, means for feeding material step by step between limits of feeding movement, and means operable during the operation of the machine for causing both limits of movement to advance each towards and away from the other to vary the length of the feed strokes during the operation of the machine.
- In testimony whereof, we have hereunto subscribed our names this 24th day of April, 1924, and this 5th day of May, 1924, respectively.

CHARLES G. BROSTROM.
